UNITED STATES PATENT OFFICE.

MATHEW ZEMAN, OF CLEVELAND, OHIO.

DOUBLE-HUNG STEEL SASH.

Application filed March 25, 1922. Serial No. 546,816.

To all whom it may concern:

Be it known that I, MATHEW ZEMAN, a citizen of the United States, residing at Cleveland, in the county of Cuyahoga and State of Ohio, has invented certain new and useful Improvements in Double-Hung Steel Sashes, of which the following is a specification, reference being had to the accompanying drawings.

10 This invention relates to improvements in double hung steel sash, and an important object of the invention is to provide in a construction of this character sash and frames so constructed that all joints at 15 points of contact are weather proof.

A further object of the invention is to provide in a construction of this character an improved construction of meeting rails for the sash which not only affords a 20 weather tight joint but which permits the use of a cylinder lock or latch for securing the windows in closed position.

A still further object of the invention is to provide an improved engagement between 25 the jamb rails and the jamb of the complete construction.

A further and more specific object of the invention is to provide a novel and efficient dividing rail joint which is weather proof 30 and which may be readily assembled.

A still further object is to provide an improved sill construction for use with windows of this character.

Other objects and advantages of the invention will become apparent throughout the course of the following description.

In the accompanying drawings wherein for the purpose of illustration is shown a preferred embodiment of my invention and 40 wherein like reference characters designate like parts throughout:

Figure 1 is a vertical sectional view taken through a double hung steel sash and frame therefor constructed in accordance with my 45 invention;

Figure 2 is an elevation thereof;

Figure 3 is a section taken on the line 3—3 of Figure 1;

Figure 4 is a perspective view showing a 50 completed joint of the dividing rails;

Figure 5 is a side elevation of the continuous member of the dividing rails;

Figures 6 and 7 are detail views showing the manner of constructing the joint of the 55 sections of the other of the dividing rails;

Figures 8 and 9 are detail sectional views

showing the manner of mounting an ordinary latch upon the meeting rails.

Referring now more particularly to the drawings, the numeral 10 designates the 60 frame, the numeral 11 the sill and the numeral 12 the frame head. In accordance with my invention, the frame 10 is divided into three separable sections, an outer section 13, the jamb portions 14 against which 65 the sash operate, and an inner section 15. Each jamb portion 14 is provided in the outer edge thereof with a notch 16 and each inner portion of the frame is provided with a notch 17, these notches, when the 70 frame sections are combined, providing grooves or slots, the purpose of which will presently appear. The metal at the edges of the slots 16 and 17 is turned outwardly 75 from the sash opening, as indicated at 18 and 19, affording guides.

The frame head or lintel is composed of a single section comprising a pair of horizontally disposed surfaces 20 and 21 connected by an integral vertical wall 24, the 80 outermost section or surface 21 being vertically offset from the section 20. The section 21 is reverted, as indicated at 23, to form a downwardly opening channel 22. The offsetting of the head frame sections 85 20 and 21 permits reception of the upper end of the upper sash 25 which is outwardly disposed with respect to the lower sash 26.

Each of the sash 26 embodies jamb rails 27, these jamb rails being substantially similar. Each is provided at its outer face with an outstanding flange or runner 28 extending into a corresponding slot of the side frame, and a portion 29 flatly abutting the jamb portion 14. The runners 28 of the 95 jamb rails operate intermediate the guides 18 or 19 of their respective flanges and are provided with shoulders 30 abutting the outer ends of these guides. Each jamb rail further embodies an inwardly directed 100 flange 31 against which the glass may be disposed.

The upper sash member 25 is provided with a head rail 32 which, when the sash is in the uppermost position, abuts the vertically offset portion of the section 20 of the frame head affording a break draft, since incoming air must necessarily pass about the head rail and downwardly past the offset 24. The head rail 32 further embodies 105 an upwardly directed flange formed upon its upper surface, as indicated at 33, which

when the sash is in its uppermost position projects into the channel 22 in the frame head and is disposed intermediate the channel walls 33. To an edge portion of this flange 33 may be secured the chains or flexible elements 34 employed for connecting the sash with a counterbalance, not herein shown. The head rail 32 further embodies an inwardly or downwardly directed flange 35 against which glass may be disposed in glazing and which combines with the flanges 31 of the jamb rail of the upper sash 25 for the reception of the glass.

The upper sash 25 is shown further provided with dividing rails 36 and 37 dividing the sash into a plurality of apertures. The dividing rail 36 has its upper end suitably jointed as at 38, to the head rail and its lower end jointed, as at 39, to the meeting rail 40 of the upper sash, the construction of which will be hereinafter described. The dividing rails 36 and 37 are each substantially T-shaped in cross section, the head 41 of the T affording glazing flanges and the stem 42 thereof sub-dividing and spacing the panes. The stem 42 of the vertical dividing rail 36 has formed therein an opening 43.

The dividing rail 37, or transverse dividing rail, is formed in two separate sections, each section having its outer end suitably jointed, as at 44, to a jamb rail 27. The inner ends of the rail sections have the head portions 41 thereof undercut, as indicated at 45, to fit against and form a close joint with the head of the rail 36, the stem portions 42 of these sections projecting to abut against the adjacent side of the stem 42 of the rail 36 and being provided with an outstanding offset flange 46 in parallel relation to the stem 42 thereof and offset from the stem a distance equal to approximately one-half its thickness, the offset of the flanges 46 of the sections being oppositely disposed so that when the sections are combined the stems 42 and head 41 thereof are aligned. In assembling the dividing rails 36 and 37, the sections of the rail 37 are arranged upon opposite sides of the rail 36 in their proper position and the flanges 46 thereof forced into the opening 43 of the stem 42 of the section 36 whereby the sections of the rail 37 are aligned and have a joint with the rail 36, the securing portion of which is disposed interiorly of the flange portions and in which there is no direct draft line formed.

The meeting rails of the sash 25 and 26 are substantially similar in construction and accordingly but one thereof is herein described. Each comprises a horizontal portion 47 provided at one side thereof with a glazing flange 48 against which the glass of its sash is to be disposed, and at the opposite side thereof with a vertically ex-

tending flange 49. The flange 49 has outstanding therefrom at its inner end, or that end disposed toward its respective sash, a flange 50 having an ogee face and which is comparatively short and at the end thereof remote from its respective sash with a flange 51 which likewise has an ogee face, the flange 51 being of such length that the flange 50 will pass the similar flange of the other meeting rail and against which the flange 51 abuts when the sash are in the closed position. Attention is directed to the fact that by this construction the flange 49 of the respective meeting rails of the sash 25 and 26 are spaced, affording room for a cylinder lock, designated at 52, although the same need not necessarily be employed, a latch being used if so desired. Each meeting rail is further provided with flanges 53 connecting the ends of the horizontal portions 47 and the flanges 49 and having at its outer face an angular flange 54 projecting into the corresponding slot of the side frame.

The sill 11 is formed of a unitary casting combining the ledge 55 and outer sill 56 having at their juncture a ridge 57, the weather face of which is sloped, as indicated at 58, the inner face of which is in the form of an abrupt shoulder 59 having a filleted connection, as at 60, with the ledge 55. The sill rail of the lower sash embodies a horizontal portion 61 abutting the flattened top of the ridge 57, a vertically directed glazing flange 62 which is directed upwardly, and a downwardly directed vertical flange 63 abutting against the outer face of the shoulder portion 59 of the ridge 57, the lower end of this flange 63 fitting against the filleted portion 60 and against the ledge 55 providing a comparatively long tortuous connection between the sill and sill rail effectually breaking any tendency to draft. The sill rail is further provided upon the face of the flange 63 with an outstanding shoulder 64 against which the upper end portion 65 of the attaching flange of the handle member 66 may be disposed whereby to take the strain of lifting the window from the fasteners 67 of the handle.

The glazing flanges of each of the sash rails have formed therein in the face thereof against which the glass is disposed, grooves 68 within which a packing medium may be disposed. If so desired, the glass may be held in position against the glazing flanges by means of angle braces 69 secured to the rails except in the case of the dividing rails, in which construction it is preferred that a U-shaped member 70 straddling the stem 42 of the dividing rail and having feet 71 abutting against the glass 72 be employed. The U-shaped member may be secured to the stem by securing elements 73 extending through the body portion thereof and engaging in the base of

the T stem of the rail. In the formation of the frame the central section 14 thereof is preferably made adjustable. In accomplishing this clamps will be provided which 5 will be bolted to the sections.

From the foregoing it is believed to be obvious that a double hung window constructed in accordance with my invention is particularly well adapted for the purpose 10 for which it is intended by reason of the fact that the same is substantially weather proof throughout, and by reason of the fact that the construction thereof is of such a simple nature as to render the same in- 15 expensive to manufacture and very durable in service. It will furthermore be obvious that the construction as hereinbefore set forth is capable of some change and modification without materially departing from 20 the spirit of my invention and I accordingly do not limit myself thereto except as hereinafter claimed.

I claim:

1. A sash embodying dividing rails each 25 substantially T-shaped in cross section and one of which is continuous and provided in the stem portion thereof with an opening, the other of said rails being formed in sections, the head portions of which have 30 a jointed connection with the head of the continuous rail, the stems of said sections being provided with projecting portions ex-

tending into said opening and maintaining the head portions thereof in alignment.

2. A sash embodying dividing rails each 35 substantially T-shaped in cross section and one of which is continuous and provided in the stem portion thereof with an opening, the other of said rails being formed in sections, the head portions thereof being undercut for the reception of the head portion 40 of the continuous rail, the stems of said sections abutting the stem of the continuous rail and being provided with projecting flanges extending into the opening thereof 45 and overlapping one another.

3. A sash embodying dividing rails each 50 substantially T-shaped in cross section and one of which is continuous and provided in the stem portion thereof with an opening, the other of said rails being formed in sections, the head portions thereof being undercut for the reception of the head portion 55 of the continuous rail, the stems of said sections abutting the stem of the continuous rail and being provided with projecting flanges extending into the opening thereof and overlapping one another, said flanges being each offset from its attached stem a distance equal to approximately one- 60 half of its thickness.

In testimony whereof I hereunto affix my signature.

MATHEW ZEMAN.
